NECKTIE HOLDER AND HANGER

Georgina G. Keeler, Chicago, Ill.

Application October 31, 1938, Serial No. 237,841

3 Claims. (Cl. 223—91)

This invention relates in general to a carrier and support for neckties and other articles of clothing and may be incorporated as a part of a clothes hanger by means of which a pair of trousers and a coat may be carried or hung at the same time.

An important object of the invention is in the provision of a necktie rack and holder for spacing ties apart so that they may be easily separated, dislodged and displayed and also held against displacement or from slipping when desired.

A further object of the invention is in the provision of a necktie rack as a part of a clothes hanger for a suit of clothes.

A further object of the invention is in the provision of a movable guard for a necktie rack which holds the ties in place and is quickly movable to withdraw any selected tie therefrom.

A still further object of the invention is in the provision of a combined hanger for neckties and suits, having means for supporting it from parallel clothes hanger rods.

A still further object of the invention is in the provision of a clothes hanger having a necktie rack as a part thereof foldable flatly together with the hanger support.

Other and further objects of the invention will appear hereinafter, the accompanying drawing illustrating preferred embodiments of the invention, in which

Fig. 1 is a side elevation of a tie rack in accordance with this invention;

Fig. 2 is a detail of the trunk supporting slide at one end of the top rail;

Fig. 3 is an enlarged view partly in section, of one end of the tie rack;

Fig. 4 is a vertical sectional view of Fig. 3; and

Fig. 5 illustrates a trunk type modification.

In a necktie holder it is desirable to space the ties apart so that they are open for display and selection, to prevent them from slipping from the rack, and to prevent the ties from longitudinal movement together in the rack whereby they become bunched and therefore soiled and wrinkled, requiring separation and redistribution along the rack.

The present invention overcomes these objections by providing a frame having a number of recesses into which neckties may be placed, and a movable guard for quickly locking them in place or movable to permit withdrawal or insertion of a tie in the rack. Usually certain ties harmonize best with a certain suit of clothes and for traveling or for general home use a tie rack of this kind may be incorporated as a part of a hanger in which the yoke for supporting the rack may also support a coat and the top or bottom edge or rail of the rack may constitute a sup-

port for one or more pairs of trousers. For traveling or for use in connection with a trunk, supporting hooks may be provided movable to engage parallel rods provided for clothes hangers in an ordinary wardrobe trunk.

Referring now more particularly to the drawing, a tie rack in accordance with this invention comprises a relatively thin frame of wood, metal, fibre, Bakelite or any other suitable material having opposite end pieces 5 and 6 spaced apart and rigidly connected by a top rail 7 and a bottom rail 8, the latter preferably circular and adapted to provide a support for ties placed loosely thereon or for trousers or other garments hung thereon.

This rack is ordinarily supported by a hanger or yoke 10, preferably a flat metal strip, pivoted at the outer edges of the end pieces by pivot screws 11 and having an upper coat hanger portion with a central supporting hook 12 secured thereto by means of which the rack is supported. As thus suspended the yoke 10 may be utilized as a coat hanger and the top and bottom rails as trousers or other garment supporters in addition to the tie rack as hereinafter set forth.

In order to hold the supporting yoke 10 in upright position a small screw or brad 13 is inserted in one or both of the end pieces and has a small head projecting from the outer side edge adapted to be seated in a recess 14 at the inner side of the supporting yoke adjacent the pivot thereof, the connection of the supporting yoke being sufficiently flexible so that it may be sprung into or out of engagement with the projecting head 13 of the stud, thus holding the supporting yoke yieldingly in position and preventing the rack from turning or upsetting with respect to the yoke.

At the inner edge of each of the end pieces is a recess 15 extending from the top downwardly and terminating in a shoulder for seating the end of a lower tie rail 16 therein. The lower tie rail is held at the bottom of the recess by a bar 17, the ends of which are seated in a recess 18 in the upper edge of the tie rail and in a recess 19 at the lower side of the top piece 7.

Also mounted at its ends in the recesses 15 is an upper tie rail 20 which has a recess 21 at each end through which the bars 17 extend to provide additional guiding means for holding the top rail in place. If desired the inner edge of each recess 15 may be provided with a strip 22 of metal or other material engaged by the ends of the tie rails 16 and 20 to prevent the movable rail from sticking in the recess or an anti-friction contact if the end pieces and rail are made of the same pieces 6. In order to hold, separate and space ties suitably apart in the rack the lower rail is formed with recesses 23 and projections 24 along its upper edge and the upper

rail is provided with corresponding projections 25 and recesses 26 adapted to inter-engage with the recesses and projections of the lower rail.

To insert, remove or adjust any tie within and between the rails 16 and 20, the upper rail is raised upon the guide rods 17, leaving the recesses 23 of the lower rail free, open and accessible for the insertion of one or more ties in any of the recesses. These recesses are preferably of sufficient width to engage the narrower or intermediate neck band portion of a tie so that the extremities thereof will hang below the lower rail on both sides thereof but are less in length than the width of most ordinary ties so that once inserted therein they are not likely to slip endwise from the recess 23 and will not slip lengthwise of the rail unless manually displaced. The upper rail is manually raised and lowered and may be held upwardly against the upper rail 7 by hand but usually there is sufficient frictional engagement between the parts to hold the movable tie rail in any adjusted position and after the upper rail is pressed downwardly against any ties in the rack they are not likely to be disengaged or dislodged from their openings or from the rack.

In traveling or for supporting this necktie rack and holder in an ordinary wardrobe trunk a pair of supports 27 are provided, one at each side of the top piece 7. Each support has an angular extremity normally seated in a recess 28 at the upper edge of the side piece 5 or 6 so that it is engaged and held in place by the yoke 10. On top of the top piece 7 a guide 29 is secured having upwardly and inwardly turned edges 30 for slidably receiving the supporting member 27 therein, the upper and inner end of the member having an up-turned projection 31 forming a finger hold for slidably moving the support inwardly and outwardly when it is not held in place by the yoke 10.

In their outermost position these supports are adapted to engage spaced or parallel side bars 32 of an ordinary wardrobe trunk or to engage any other similar supports, and the tie rack may thus be carried in the trunk without tilting or dislodging the ties therefrom. When upheld by the supports 27 the supporting yoke 10 is turned downwardly below the rack and below the bottom rail 8 as indicated in Fig. 1.

If this type of combined coat and tie hanger is desired primarily for use in a trunk the upper portion, as shown in Fig. 5, may be made of a single piece of metal, pressboard, laminated wood or the like, having supporting arms 51 with notches 52 at the under sides of the outer ends for supporting it from parallel trunk bars or hooks, coat hanger portions 53 and a bottom cross rail 54. In the top is a recess 55 for seating a central supporting hook 56 which engages one end of the recess in raised position. At the bottom is the tie rack proper including side pieces 5, bottom rail 8, lower and upper tie rails 16 and 20, connected at the lower ends of hanger portions 53.

With these constructions it is apparent that the tie rack may be used alone, it may be used in connection with the hanger, or with the end supports 27, or with a clothes hanger for a trunk; it is designed and intended to be incorporated as a part of a clothes hanger for a suit, and thus to provide a rack for neckties adapted to be used particularly with that suit or separately therefrom with any suit.

It is obvious that the rack and holder may be constructed of various material and of various sizes, and for ties or similar articles of various shapes and widths without departing from the spirit and scope of the invention.

I claim:

1. A rack for supporting neckties comprising a frame including end pieces, a lower crossbar having spaced apart recesses in the upper edge thereof to receive neckties hung therefrom, and a companion crossbar slidable vertically in the frame above the necktie supporting bar and having downward projections correspondingly spaced apart with respect to the aforementioned recesses to engage the neckties and clamp them within the recesses, whereby the recesses prevent lateral movement of the neckties on the supporting bar and the projections on the slidable bar prevent longitudinal movement thereof when clamped in the rack; together with means associated with the rack for supporting the same and including a yoke pivoted to the ends of the frame for suspending the rack, and means projecting from the ends of the frame adapted to cooperate with the yoke to prevent swinging or tilting of the rack when suspended.

2. A rack for supporting neckties comprising a frame including end pieces, a lower crossbar having spaced apart recesses in the upper edge thereof to receive neckties hung therefrom, and a companion crossbar slidable vertically between the end pieces in the frame above the necktie supporting bar and having downward projections correspondingly spaced apart with respect to the aforementioned recesses to engage the neckties and clamp them within the recesses, whereby the recesses prevent lateral movement of the neckties on the supporting bar and the projections on the slidable bar prevent longitudinal movement thereof when clamped in the rack; together with means associated with the rack for supporting the same and including a yoke pivoted to the ends of the frame below the upper edges thereof, and members extensible beyond the ends of the frame and movable respectively from a position within the confines of the yoke to a position beyond the ends of the frame when the yoke is swung out of the path of said members.

3. In a combined clothes hanger and rack for supporting neckties, a frame including end pieces, an upper crossbar, and a lower crossbar, the lower crossbar having spaced apart recesses in the upper edge thereof to receive neckties hung therefrom; an intermediate crossbar slidable vertically in the frame above the necktie supporting bar and having downward projections correspondingly spaced apart with respect to the aforementioned recesses to engage the neckties and clamp them within the recesses to prevent displacement thereof, and a yoke for holding clothes associated with the frame, said yoke having a central supporting hook, downwardly inclined sides, and parallel portions at the ends thereof pivoted to the ends of the frame so that the yoke may be turned downwardly below the frame; together with longitudinally movable supporting hooks at the ends of the upper crossbar of the frame, said hooks being normally disposed inwardly within the confines of the yoke and movable outwardly to project beyond the ends of the frame for supporting it when the yoke is turned downwardly.

GEORGINA G. KEELER.
